Primary Examiner — Karen S Acker*Assistant Examiner* — Omeed Agilee(74) *Attorney, Agent, or Firm* — Husch Blackwell LLP(57) **CLAIM**

The ornamental design for an optical sight reticle, as shown and described.

DESCRIPTION

FIG. 1 is a front perspective view of a first embodiment of an optical sight reticle showing my new design;

FIG. 2 is a front elevation view thereof;

FIG. 3 is a rear elevation view thereof;

FIG. 4 is a right elevation view thereof; the left elevation, the top plan, and the bottom plan views being identical with FIG. 4;

FIG. 5 is a front perspective view of a second embodiment of an optical sight reticle showing my new design;

FIG. 6 is a front elevation view thereof;

FIG. 7 is a rear elevation view thereof; and,

FIG. 8 is a right elevation view thereof; the left elevation, the top plan, and the bottom plan views being identical with FIG. 8.

The broken lines in the drawings depict environmental subject matter and form no part of the claimed design.
